UNITED STATES PATENT OFFICE.

ALBEN E. LUNDELL, OF NEW YORK, N. Y., ASSIGNOR, BY MESNE ASSIGNMENTS, TO
WESTERN ELECTRIC COMPANY, INCORPORATED, A CORPORATION OF NEW YORK.

SEMI-AUTOMATIC TELEPHONE SYSTEM.

1,233,892.

Specification of Letters Patent. Patented July 17, 1917.

Application filed November 6, 1915. Serial No. 60,002.

To all whom it may concern:

Be it known that I, ALBEN E. LUNDELL, a citizen of the United States, residing at New York, in the county of Bronx and State of New York, have invented certain new and useful Improvements in Semi-Automatic Telephone Systems, of which the following is a full, clear, concise, and exact description.

10. This invention relates to telephone systems, and particularly to telephone systems of the semi-automatic type. It is desirable in semi-automatic telephone systems to have the operator's sending apparatus so arranged that if the operator has assigned a particular link circuit or cordless trunk to a calling subscriber, she may be able to recall such assignment at will and assign a different trunk either to the same or some other calling subscriber.

15. This invention relates to telephone systems, and particularly to telephone systems of the semi-automatic type. It is desirable in semi-automatic telephone systems to have the operator's sending apparatus so arranged that if the operator has assigned a particular link circuit or cordless trunk to a calling subscriber, she may be able to recall such assignment at will and assign a different trunk either to the same or some other calling subscriber.

The object of the invention, therefore, is to provide an operator's sending apparatus in which the assignment of a link circuit or cordless trunk frees the sender on a previously assigned trunk in case such trunk is not freed by the normal operation of the keys.

In the drawings, Figures 1, 2 and 3, arranged Fig. 2 to the right of Fig. 1 and Fig. 3 below Fig. 2, illustrate the invention as applied to a telephone system, only so much of the telephone system being shown as is necessary for an understanding of the invention. For a detailed description of a telephone system to which this invention is applicable, reference may be had to Patent No. 1,125,579 of January 19, 1915 granted to F. R. McBerty.

A description of the operation of assigning a link circuit or trunk, the recalling of such assignment and the substitution therefor of another trunk, will be described in detail, as it is thought by this method the invention will be most clearly understood.

45. A subscriber, the number of whose station is 100, wishing to speak with any other subscriber of the system, as subscriber whose station is numbered 7180, removes his receiver from the switchhook, lighting in the usual manner the signal lamp at the central office. The "A" operator located at 102, observing the lamp lighted, inserts a plug into the jack individual to the calling subscriber and depresses the listening key 103, placing

herself in communication with the calling subscriber. The calling subscriber informs the A operator of the number of the subscriber with whom he wishes to speak, whereupon the A operator depresses the key 104, connecting herself with the B operator at position 105. She repeats to the B operator the information she has already received from the calling subscriber, whereupon the B operator informs the A operator of the number of the trunk she proposes to assign to the calling subscriber, as trunk 47. Simultaneously therewith she depresses the key associated with said trunk and to which the numeral 201 has been given. The A operator then inserts the plug 106 into the jack 107, thus connecting the line of the calling subscriber to the trunk 47. After assigning the trunk the "B" operator sets up on her keyboard the number of the wanted subscriber, and it is assumed that such number is 7180. The depression of the key 201 closes a circuit from battery, motor magnet of sequence switch 202, conductor 203, lower left contact of sequence switch spring 204, conductor 205, the depressed key 201 to ground, moving sequence switch 202 from position 1 into position 2. In position 2 of this sequence switch a circuit is closed from battery, motor magnet of sequence switch 300, conductor 301, upper left contact of sequence switch spring 302, conductor 303, lower right contact of sequence switch spring 206, conductor 207, right armature and back contact of disconnect relay 208 to ground, moving sequence switch 300 from position 1 into position 2.

On sequence switch 300 coming into position 2, circuit is closed from battery, relay 304, conductor 305, upper left contact of sequence switch spring 306, conductor 307, brush 308, contact 309, conductor 310, lower right contact of sequence switch spring 209, conductor 207, right armature and back contact of disconnect relay 208 to ground. Relay 304 energizes, attracting its armature and completing a circuit from battery, motor magnet of sequence switch 300, conductor 301, lower left contact of sequence switch spring 302, conductor 312, right armature and front contact of relay 304 to ground, moving the sequence switch 300 from position 2 into position 3, in which position the operator having depressed the keys corre-

sponding to No. 7180, a circuit is closed from battery, motor magnet of sequence switch 300, conductor 301, upper right contact of sequence switch spring 302, the contacts closed by the depressed keys 7180 to ground, moving sequence switch 300 from position 3 and into position 7.

As the sequence switch moved into position 4 and until it leaves position 6, a circuit is closed from battery, release magnet 328, conductor 329, upper right contact of sequence switch spring 327 to ground, releasing the depressed keys.

In position 7 of sequence switch 300, a circuit is closed from battery, line relay 210, upper right contact of sequence switch spring 211, conductor 212, contact 313, brush 314, conductor 315, upper right contact of sequence switch spring 316, relay 317, conductor 318, brush 319, terminal 320, conductor 321, lower right contact of sequence switch spring 213 to ground, energizing the line relay 210 which, at its armature and front contact, closes an energizing circuit for the motor magnet of sequence switch 202, moving the same from position 2 into position 3, from which point the call progresses in the usual manner and as particularly described in the patent above referred to.

It may be, however, that the "B" operator becomes confused as, for example, when several "A" operators connect at the same time with her talking apparatus, and the directions she receives under these conditions are not clear to her, so that after assigning a particular trunk to a calling subscriber she wishes to recall such assignment. If, therefore, she has assigned a trunk and is in doubt as to whether or not it is the proper trunk to be assigned, she may take orders from a subsequent "A" operator, paying no attention to what has been done before. She then assigns to the last calling subscriber a different trunk, as trunk 53, the assignment of which is controlled by the key 215. It is assumed in this case that the complete number on the first assignment has not been set up by the operator, and that apparatus shown in Fig. 3 is in position 3 while the apparatus shown in Fig. 2 is in position 2. The depression of the key 215 closes a circuit from battery, disconnect relay 208, conductor 216, upper right contact of sequence switch spring 217, key 201, conductor 218, key 215 to ground, energizing the disconnect relay 208, which locks up at its left armature and front contact, upper left contact of sequence switch spring 219, which remains closed until sequence switch 202 passes out of position 11. The energization of the disconnect relay 208 closes a circuit for the motor magnet of sequence switch 202 from battery, motor magnet, conductor 203, upper left contact of sequence

switch spring 204, conductor 240, right armature and front contact of disconnect relay 208 to ground, moving the sequence switch 202 from position 2 and into position 6. The disconnect relay 208 being energized by the depression of the trunk key 215, the energizing circuit for the relay 304 is broken at the right armature and back contact of the disconnect relay, whereupon the armatures of relay 304 retract, closing a circuit from battery, motor magnet of sequence switch 300, conductor 301, upper right contact of sequence switch spring 322, conductor 323, right armature and back contact of relay 304 to ground, moving sequence switch 300 from position 3, through position 16 and into the position 17, in which position a circuit will be closed from battery, return magnet 326, lower right contact of sequence switch spring 327, to ground. The energization of this magnet moves the brushes 308, 314, 319 to their initial position, at which point the normal contact 325 is closed, completing a circuit from battery, motor magnet of sequence switch 300, lower right contact of sequence switch spring 302, conductor 324, normal contact 325 to ground, moving sequence switch 300 from position 17 into position 1.

In passing through position 4, a circuit will be closed from battery, release magnet 328, conductor 329, upper right contact of sequence switch spring 327 to ground, energizing the release magnet and allowing any depressed key or keys to return to normal.

In the meantime, a circuit is closed from battery, motor magnet 220, conductor 221, armature and back contact of relay 222, upper right contact of sequence switch spring 206, conductors 207 and 223, upper right contact of sequence switch spring 213 to ground, energizing said drive magnet and moving the brush carriage until the arm 224 contacts with the segment 225, at which point in the operation the following circuit is closed: battery, resistance 226, lower left contact of sequence switch spring 227, conductor 228, segment 225, arm 224, conductor 229, lower left contact of sequence switch spring 230, relay 222, upper right contact of sequence switch spring 209, conductors 207 and 223, upper right contact of sequence switch spring 218 to ground, energizing relay 222, breaking the circuit for drive magnet 220, stepping the brush carriage, and completing a circuit from battery, motor magnet of sequence switch 202, conductor 203, armature and front contact of relay 222, upper right contact of sequence switch spring 206, conductors 209 and 223, upper right contact of sequence switch spring 213 to ground, moving sequence switch 202 out of position 6 and into position 7, in which position a circuit will be closed from battery, motor magnet of se-

quence switch 202, conductor 203, upper left contact of sequence switch spring 204, conductor 240, right armature and front contact of disconnect relay 208, to ground, moving sequence switch 202 from position 7, through position 8 and into position 9.

In position 9, the circuit above traced for relay 222 is again closed, completing a circuit from battery, motor magnet of sequence switch 202, conductor 203, armature and front contact of relay 222, upper right contact of sequence switch spring 206, conductors 207 and 223, upper right contact of sequence switch spring 213 to ground, moving the sequence switch into position 10, in which position the energizing circuit for relay 222 is broken at the lower left contact of sequence switch spring 227, and the energizing circuit for motor magnet of sequence switch 202 is established at the upper left contact of sequence switch spring 204 to move sequence switch 202 through position 11 and into position 16.

In position 16, a circuit is again closed, in the manner above described, for the driving magnet 220 to move the brush carriage into its normal position, where a circuit is closed from battery, resistance 226, upper left contact of sequence switch spring 227, arm 224, conductor 229, lower left contact of sequence switch spring 230, relay 222, upper right contact of sequence switch spring 209, conductor 207, right armature and back contact of relay 208 to ground, energizing the relay 222, which, at its armature and front contact, again closes a circuit to move sequence switch 202 from position 16 to position 18.

In position 18 a circuit is closed from battery, motor magnet of sequence switch 202, conductor 203, lower right contact of sequence switch spring 214, armature and back contact of line relay 210 to ground, moving sequence switch 202 from position 18 into position 1, where it is entirely disconnected from the previously assigned trunk and is now under control of the last assigned trunk, and where the operation takes place in the manner heretofore described.

To provide for taking care of a call to which a trunk has been assigned and then recalled, the operator may transfer such call over to a supervisor, who will take care of the same in the usual manner, but since this forms no part of the present invention it will not be described in detail.

What is claimed is:

1. In a telephone exchange system, an operator's sending apparatus, a plurality of trunks, means associated with each trunk for connecting the same to said sending apparatus to extend a call, and means associated with said sending apparatus for freeing the same from a connected trunk when operated

prior to the sending operation, said means being operated in response to the operation of the connecting means associated with another trunk.

2. In a telephone exchange system, a plurality of trunks, a sending apparatus common to said trunks, means associated with each trunk adapted, when operated, to cause connection of said sending apparatus with the corresponding trunk, means for causing operation of said sending apparatus, and means responsive to the operation of the said means associated with each of said trunks of another of said trunks prior to the operation of said sending apparatus to cause disconnection of said sending apparatus from a trunk.

3. In a telephone exchange system, a plurality of trunks, a sending apparatus common to said trunks, means associated with each trunk adapted, when operated, to cause connection of said sending apparatus with the corresponding trunk, means for causing operation of said sending apparatus, and means responsive to the operation of the said means associated with each of said trunks of another of said trunks prior to the operation of said sending apparatus to cause disconnection of said sending apparatus from connection with a connected trunk and to cause connection of said sending apparatus with said other trunk.

4. In a telephone exchange system, a central office, a plurality of subscribers' lines terminating thereat, a plurality of "A" operators' positions at said central office adapted to be connected to any of the subscribers' lines, a "B" operator's position at said central office accessible to any of the "A" operators, a plurality of trunks extending between said "A" and "B" operators' positions and having a sending apparatus common thereto, means operable by a "B" operator individual to each trunk for associating the common sending apparatus with such trunk, and means associated with the said sending apparatus actuated by the associating means individual to another trunk before the first sending operation is completed for disassociating the first said trunk and the sending apparatus, and associating another trunk therewith.

5. In a telephone exchange system, a central office, a plurality of subscribers' lines terminating thereat, a plurality of "A" operators' positions at said central office adapted to be connected to any of the subscribers' lines, a "B" operator's position at said central office accessible at any of the "A" operators' positions, a plurality of trunks extending between the "A" and "B" operators' positions and having a sending apparatus common thereto, means operable by the "B" operator for initiating the sending operation, means connected to any trunk and un-

der the control of the "B" operator for causing the connection of said trunk to the sending apparatus, means operable by the "A" operator for connecting said trunk to a calling subscriber's line, and means associated with said sending apparatus and actuated by the means connected to another trunk, and prior to the initiation of the sending

operation, for disassociating the first said trunk from the sending apparatus and associating the second said trunk therewith. 10

In witness whereof, I hereunto subscribe my name this fifth day of November, A. D. 1915.

ALBEN E. LUNDELL.
